UNITED STATES PATENT OFFICE.

CHARLES C. SPREEN, OF DETROIT, MICHIGAN, ASSIGNOR, BY MESNE ASSIGNMENTS, TO KELVINATOR CORPORATION, OF DETROIT, MICHIGAN, A CORPORATION OF MICHIGAN.

AUTOMATIC OILING DEVICE.

Application filed October 10, 1923. Serial No. 667,612.

To all whom it may concern:

Be it known that I, CHARLES C. SPREEN, a citizen of the United States, residing at Detroit, in the county of Wayne and State of Michigan, have invented a certain new and useful Improvement in Automatic Oiling Devices, of which the following is a full, clear, and exact description, reference being had to the accompanying drawings.

Recent years have witnessed the introduction and widespread use of mechanical power in establishments not provided with attendants skilled in the operation and maintenance of power devices. It is obvious that under these conditions it is essential that these power devices require the minimum attention both for operation and maintenance. Heretofore various modifications have been made to partially accomplish this object but so far as I am aware at the present time there has been suggested no satisfactory method of supplying oil to the machinery over a long period of time. My invention provides means to accomplish this result. In the drawings accompanying this specification and forming a part thereof I have shown, for purposes of illustration, certain physical embodiments which my inventive concept may assume and, because the electric motor is probably the power device most frequently encountered in establishments of the type herein considered, I have shown all but one of these illustrative embodiments as applied to an electric motor.

In these drawings:

Figure 1 shows one form of my invention adapted for use with a power device employing a packed oil receptacle, while

Figures 2, 3, and 4 are sectional views showing modified forms of my invention.

The present application is a continuation in part of my application Serial Number 643,518 filed June 5, 1923.

Under certain circumstances it may be convenient to employ a container other than the usual oil can shown in said copending application, and particularly a container of the type in which oil may be purchased in quantities, and in Figures 1 and 2 herein I have shown installations designed more particularly to receive such containers and for purposes of illustration have shown these installations as adapted for use with that type of power device provided with oil cups

rather than that type which is provided with oil wells although it will be readily apparent that the installations shown in Figures 1 and 2 herein may be employed as modifications of the installation shown in Figures 1 and 2 of said copending application just as readily as they may be employed as modifications of the installation shown in Figure 3 of said copending application.

The installation shown in Figure 1 comprises a fitting 70 provided with a duct 71 arranged to enter within an aperture 58 in the upper end 59 of the oil cup 51 and support the entire fitting 70 from the oil cup 51 by means of screw threads 72 and 61 carried respectively by the outer surface of the duct 71 and the inner surface of the aperture 58 of the oil cup 51. This fitting 70 is provided above the duct 71 with a receptacle 73 formed by a tubular extension 74 rising above the duct 71 and adapted to receive the cap 75 of an oil receptacle 76 and in this manner support the container 76 in operative position. At a point below the lower face of the cap 75 the fitting is interrupted by the entrance of a duct 77 leading from the receptacle 73 to the atmosphere.

In employing this installation it will be found convenient, after forming in the cap 75 an aperture 78, to remove the cap 75 from the container 76 and position therein a simple valve mechanism which may consist of an ordinary nail 79 inserted through a disk 80 of any suitable material such as cork or rubber and operable, while the container 76 is being positioned within the fitting 70, to prevent the flow of oil from the container 76 until the container 76 has been inserted into the fitting 70 to such an extent that the head of the nail 79 strikes the lower face of the receptacle 73 after which further insertion of the container 76 causes the nail 79 to lift the disk 80 away from its sealing position across the aperture 78 and freely open the aperture 78.

It will be understood that after the container 76 is thus positioned upon the fitting 70 oil will flow from the container until the oil level within the receptacle 73 rises above the opening into the receptacle 73 of the duct 77 and in this manner cuts off the supply of air into the container 76 and thereby terminates the flow of oil from the container 76 until such time as the level of the oil

within the receptacle 73 falls below the opening of the duct 77 into the receptacle 73 at which time the action will be repeated to bring the oil to its previous high level.

6 The installation disclosed in Figure 2 is identical in construction and operation with that disclosed in Figure 1 but omits the valve mechanism utilized to seal the aperture 78 as the container 76 is being placed 10 within the fitting 70.

The installation disclosed in Figure 3 is particularly designed for use as an alternative to the installation disclosed in Figures 1 and 2 of said copending application and 15 provides, instead of the installation disclosed in Figures 1 and 2 of said copending application, a short fitting 81 arranged to be tapped into the oil well 22 in the same manner in which the duct 29 is tapped there 20 into, provided with a screw threaded upwardly opening aperture 82 arranged to receive a correspondingly screw threaded neck 83 on a container 84, and provided adjacent the opening 82 with a vent 85 opening 25 to the atmosphere. The operation of this embodiment of my invention is in all respects similar to the operation of the embodiment disclosed in Figures 1 and 2 of said copending application.

30 The installation disclosed in Figure 4 shows the oiling apparatus disclosed in Figure 3 applied to the oiling of an idler pulley 86 rotating between a supporting member 87 and the head 88 of the stud 89 which 35 acts as the bearing for the pulley 86 and is secured to the support 87 by means of a stem 90 which passes through an aperture 91 in the support 87 and is screw threaded to cooperate with a nut 92 arranged to 40 clamp the supporting member 87 between itself and the shoulder 93 of the stud 89. In this installation the fitting 81 is inserted into the screw threaded opening 94 in the end of the stud 89 to permit the oil from 45 the receptacle 84 to flow into the cavity 95 within the stud 89 and from this cavity 95 through a duct 96 onto the bearing surface.

In the installations shown in Figure 3 and in Figure 4 the oil will flow from the recep-

tacle 84 into the fitting 81 until the oil seals 50 the vent 85 whereupon further flow will be prevented until the oil level drops below the entrance of the vent 85 into the fitting 81.

It will be apparent to those skilled in the art that I have provided a simple and satisfactory method of supplying a large quantity of oil to devices of the type herein considered and particularly to electric motors of the type using an oil well or to electric 60 motors of the type using an oil cup or to idler pulleys mounted upon a stud provided with an interior oil or grease cavity. It will also be apparent to those skilled in the art that the installations herein illustrated 65 may be variously modified, particularly by interchanging various features of one installation for corresponding features of another installation, all without sacrificing the advantages or departing from the spirit of 70 my invention. The disclosure herein is therefore illustrative only and my invention is not limited thereto but on the contrary comprehends any installation arranged to accomplish the objects of my invention by 75 equivalent instrumentalities.

I claim:

An oiling device comprising an oil container of the type having an outlet passageway screw threaded on its exterior to receive a cooperatively screw threaded closure member; a fitting having an inlet passageway screw threaded interiorly and cooperatively receiving said screw threaded passageway and thus supporting said container from said fitting, provided with a chamber 80 into which said outlet passageway extends, provided with an opening to the exterior disposed above the level of the opening of 85 said outlet passageway, and above said chamber, and provided with an outlet opening 90 emerging through a duct-like projection arranged to be inserted into the inlet opening of an oil cup; and an oil cup into the inlet opening of which said projection is operatively secured.

In testimony whereof, I hereunto affix my signature.

CHARLES C. SPREEN.
